COKE OVEN LEVELER DOOR

Heinrich Koppers, Essen, Germany, assignor, by
mesne assignments, to Koppers Company, Pitts-
burgh, Pa., a corporation of Delaware

Application April 1, 1938, Serial No. 199,344
In Germany April 3, 1937

2 Claims. (Cl. 202—248)

The present invention relates to doors for horizontal chamber or retort ovens for the production of gas and coke and more particularly to those coke oven doors which are provided with 5 a closable opening through which the so-called leveling beam may be travelled into the coking chamber.

In order to level the coal or other fuel charged into the coking chamber so that a gas collecting 10 space is formed along the whole length of the oven in the upper part of the chamber to withdraw the distillation gases, the leveling beam is usually made use of. This beam has substantially the same length as the chamber. It is 15 pushed into the chamber through an opening provided in the chamber door and then moved forwards and backwards several times, until the surface of the coal charge in the chamber has been leveled to the necessary extent. The opening 20 provided in the chamber door through which the leveling beam is introduced into the chamber, is provided with suitable closure means, for instance a lid or flap carried by a hinge.

The leveling hole lid is impinged on its inner 25 side by the distillation gases and vapours. Thereby, condensations of tarry constituents may be formed on the lid and on the sealing face of the doors against which the rim of the lid fits tight. For the purpose of removing the deposits 30 from the inside of the lid and from the sealing face of the door, much manual work has to be performed.

The main object of my present invention now 35 consists in the provision of an improved design for the said leveling hole lids or flaps of coke oven doors by which the above difficulties will be overcome.

The principal feature of my present invention 40 is to provide the leveling hole lid with a refractory liner which engages in the leveling hole like a plug, and to arrange this lid on operating levers moving upwards in such a manner that the lid without altering its position relatively to the vertical is opened first of all in an essentially horizontal direction and then, after the refractory liner has left the range of the leveling 45 hole, the lid is lifted upwards.

Many other essential objects and features of 50 my present invention will be apparent from the following description of a preferred embodiment and may be taken therefrom and from the accompanying drawings, in which:

Figure 1 is a vertical section through a coke oven door,

Figure 2 is a front view of the coke oven door,

Figure 3 shows in an enlarged scale the proper leveling hole closure in front view, and

Figure 4 finally shows a vertical section on line IV—IV of Figure 3.

The coking chamber of the coke oven shown in 5 Figure 1 has been marked 1 on the drawings. The chamber 1 is formed by the side walls, the top 2 and the bottom 3 built of refractory material. The coking chamber has on both sides a doorway each of which is closed by a door. The 10 door comprises a body 4 consisting of iron or steel which is equipped on its inner side with a refractory liner 5. The door 4 is held in closed position by the latch bars 6 or other suitable means. After loosening the latch bar 6, the 15 door may be extracted from the chamber opening by a slight lifting and a subsequent withdrawing in the direction of arrow 7 which for instance happens if the chamber is to be discharged.

In order to be able to fill the chamber 1 with 20 the fuel to be carbonized, charging holes are arranged in the oven roof. For simplicity, the charging holes have, however, not been shown on the drawings. When the fuel, for instance finely 25 grained coal, is charged through the charging holes into the chamber, cones reaching up to the top of chamber 1 are finally formed on the top of the mass of charged in coal. These so-called filling cones must be done away with so that the gases and vapours developed during the carbonization process, may pass without any trouble into the ascension pipe which is arranged either at the one chamber end, in the middle of the chamber, or at any other suitable place in the roof 2.

The surface of the chamber charge is usually 30 leveled by the means of a leveling beam which is introduced from the side into the oven chamber. A free space, being termed the gas collecting 35 space, is formed along the whole length of the oven in the upper part of the chamber by the backward and forward movement of the leveling beam. The leveling beam is carried on a framing arranged in most cases in such a manner that it 40 travels in front of the oven. This leveling beam is essentially of the same length as the chamber so that it can remove all the coal from the gas 45 collecting space extending over the length of the oven chamber.

An opening 8 has been provided above the coke oven door so that the leveling beam can be introduced into the chamber (see Figure 1). A closure 9 or lid serves to shut-off the door opening. Figures 3 and 4 show in detail the construction of the closure 9 (of Figure 1).

The leveling hole closure consists of a steel 55

lid 10 which on its inner side is fitted with projections 11 holding a refractory liner 12. The leveling hole 8 is surrounded by a door casing 13, which is suitably affixed to the door frame 4' for the door body 4.

At the upper end, the lid 10 is equipped with two lateral carrying-pins 14, which are engaged by the carrying levers 15. The other end of the carrying lever 15 is fixed to a shaft 16 which is supported in eyes of supports 17 provided on the leveling hole door casing 13.

Furthermore, the operating lever 18 is fastened to the shaft 16 to manipulate the leveling hole lid. The lever 18 further engages a pin 19 which is pivotally movable in 18 and which, through bearings 20, is fastened to the lid 10, and which lies on the same line with the carrying pins 14.

The lever 18 carries a closing lever 21 on its lower end projecting somewhat beyond the lid and the door casing. The lever 21 is fitted with an extension 22 which carries a web 23. In order to keep the lid in closing position, the web 23 is moved behind a nose 24 provided therefor on the lower coke oven door frame 4' below the leveling hole door casing 13.

At the outer end of the lever 21 is situated a web 25 for engagement by the device for opening the leveling hole lid 9.

30 The apparatus according to Figures 3 and 4 works principally as follows:

In order to open the leveling hole, first move the lever 21 in such a manner that the web 23 lies outside the range of the nose 24. Then the operating lever 18 is turned around the centre of the shaft 16. At the beginning of this movement of lever 18, the lid 10 together with the affixed refractory liner 12 is withdrawn from the leveling hole 8 in an essentially horizontal direction. During this and the following moving period of the lever 18, the lid 10 maintains practically its position towards the vertical direction as shown on the drawings, i. e., the lid moves or swings relatively to the lever 18 around the axis 45 of the pins 14, 19, i. e., the lower end of lever 18 moves away to the left of 10 until 18 is at right angles to lid 10, the latter hanging down pendant fashion but in its original position with respect to the vertical that it must have for sealing the door opening. In this position, the lid 50 is moved upwards so far until it lies outside the range of the leveling hole 8 so that the leveling beam may be introduced into the leveling hole without any trouble.

55 Also during the closing movement, the lid maintains its original position towards the vertical line. This is of advantage insofar as the refractory liner 12 cannot fall out of the arms 11 of the lid 10.

60 If the closure of the leveling hole trap be constructed as a trap door as represented by the usual type of construction, the refractory liner

might become loosened each time when opening the closure since it does not rest any more on the lower brick holders 11, but it is situated between both the brick holders 11 similarly to a suspension ceiling.

5 My present invention has now been described above by exemplifying it in connection with an ordinary coke oven door. It may, however, also be adopted for other kinds of coke oven doors and it is also possible to arrange the leveling hole and its casing as a part of the coke oven door proper.

10 The invention is not limited in all its aspects to the mode of carrying it out as described and shown, since it may be variously embodied within 15 the scope of the following claims.

I claim:

1. Coke oven leveler door construction comprising a leveler door frame, a door-lid therefor, a hinged lever for moving said door lid into and out of closing position with the leveler door 20 frame, said lever being hinged above the door lid and extending downwardly therefrom over the outside of the lid to press the lid in closed position and latch means below the lid for securing the lever and lid in closed position, the lid being 25 connected with the hinged lever only at a point above the vertical center of the lid by means of a pivotal connection so as to have the lid swing pendants from the lever in the original position 30 of the lid to the vertical during opening and closing movements of the lever.

2. Leveling hole closure for horizontal chamber ovens for the production of gas and coke, comprising a substantially vertically disposed closing lid connected to a hinge which hinge is 35 mounted to swing about a horizontal axis, said lid having on its inner side a retainer for a refractory plug, and within the retainer a refractory liner plug projecting laterally from the lid for insertion into the leveling doorway, said lid 40 being also connected with an upwardly movable operating lever which is mounted to pivot about a horizontal axis at about the axis for the hinge and which is constructed in such manner that on the initial upward movement and final downward movement of the lever the lid is moved horizontally, without considerable change in its original inclination to the vertical, in withdrawing and inserting the liner plug in the leveling doorway; characterized by the lid being pivotally 45 connected with the hinge and with the operating lever so as to hang pendants therefrom in its original position for closing and thereby sustain the liner plug on its retainer in their 50 normal position to the vertical during the rest of the lifting and lowering positions of the operating lever, said operating lever extending downwardly over the lid in closed position, and latching means cooperating with the operating lever to hold the lever and lid in closed position.

60

HEINRICH KOPPERS.
